APPARATUS FOR ELEVATING CAPPED
TUBES OR SIMILAR CONTAINERSBror Emil Johnson, Alsten, Sweden, assignor to
Aktiebolaget Gerh. Arehns Mekaniska Verk-
stad, a Swedish joint-stock companyApplication December 4, 1936, Serial No. 114,257
In Sweden December 14, 1935

5 Claims. (Cl. 226—129)

This invention relates to an apparatus for elevating capped tubes or similar containers into position for further treatment, for instance to be filled with paste or other material, or for turning.

5 It is an object of my invention to provide means for safely placing collapsible tubes onto a spout for delivery thereto of paste, oil, etc. or into operative position relative to a tube turning member without necessitating guides for the tube as 10 said means will automatically adjust the tube into proper position relative to the delivery spout or turning member.

Another object of my invention is to provide 15 means for safely removing collapsible tubes or like containers from the delivery spout or turning member even though the tube may have stuck to said spout or member.

A further object of the invention is to provide 20 means for safe control of the withdrawal of collapsible tubes during their supply with material from a delivery spout enclosed by the tube.

Still another object of the invention is to provide 25 improved means for gripping tube caps having a large width and to permit the gripping means to move together with the tube upwards through a comparatively narrow tube holder.

With these and other objects in view the invention comprehends the construction as herein-after described and illustrated by way of example 30 in the drawing.

In the drawing:—

Fig. 1 is an elevation partly in section of the apparatus, and

Fig. 2 is a plan view of part of the mechanism 35 and a tube conveyor.

Referring to the drawing, showing by way of example the apparatus according to the invention used in a device for filling collapsible tubes, the empty tubes A which are inserted into sleeve-shaped carriers I on a chain conveyor 2 are moved stepwise in the direction of the arrow (Fig. 2) one after another into position between a material delivery spout or pipe 3 and an elevator mechanism.

45 The elevator mechanism comprises a spindle 4 having formed at its upper end a concave button 5 which constitutes a tube supporting member. A cross pin 6 is inserted into the lower flattened end of the spindle 4 and is straddled by the legs of a fork 7 which embraces the spindle and prevents said spindle from turning about its axis. The fork 7 constitutes the end of an arm 8 of a bell-crank lever which is mounted on a rotatably journalled shaft 9. The other arm 10 of the lever 50 carries an anti-friction roller 21 which rides upon

a cam disc 13 which is secured to a continuously revolving driving shaft 12. The roller 21 is pressed against the cam disc 13 by a tension spring 11 one end of which is connected to the lever arm 10, and the other end to a guide 19 for 5 the spindle 4.

The upper end of the spindle 4 and the button 5 are enclosed by a sleeve shaped holder 14 to which are secured two oppositely arranged hooks 15. The holder 14 is axially movable on the 10 spindle 4 and has a widened bore 16 in which is inserted a contractile spring 17. The spring 17 seats on a lower abutment 18 in the holder and an abutment formed on the button 5 so that the holder 14 will be resiliently pressed against 15 the guide 19 when the spindle 4 is at the position illustrated in Fig. 1.

The tube carriers I have longitudinal slots 22 and 23 which permit the hooks 15 to move longitudinally up and down therethrough. To support the tubes before elevating them the carriers I have a forked plate 20 between the legs of which the holder 14 together with the hooks 15 can move up and down. As the carriers I are slotted to form passages for the holder hooks 15 25 even tubes having caps of almost the same width as the tube can be lifted by the elevator mechanism, and this is an advantage in view of the fact that a wide tube cap can be more correctly gripped by the pincher formed by the hooks 15 30 and the button 5 than a small cap.

The tube A is moved sidewise so that its cap B enters the open pincher when the different parts of the mechanism are at the positions shown in Fig. 1. Thereafter, the spindle 4 ascends so that 35 the button 5 will first hit the cap B and elevate the tube somewhat so that the cap will be yieldingly clamped between the button 5 and the hooks 15. Thereby the tube will be held erect in the case where the tube does not fit the carrier I 40 closely so that said tube will be exactly coaxial with the material delivery spout or pipe 3. When the spindle 4 moves further in an upward direction the holder 14 is lifted and the spring 17 will yieldingly retain the cap B of the tube between 45 the button 5 and the hooks 15. Thereby the tube is raised through the carrier I and placed onto the spout 3. As the tube A is held by the elevator members in a correct vertical position any special 50 tube guides hitherto used can be omitted and the carriers I can be short and wide so that the empty tubes may be easily inserted by hand into them.

Whilst material is being supplied, the tube is gradually lowered and withdrawn from the pipe 3 by a downward movement of the spindle 4. 55

This withdrawal is effected positively by the hooks 15 which ensures that the tube does not stick to the pipe 3 but it is safely drawn off the latter. The downward movement of the tube A can be regulated as desired by suitably shaping the cam disc 13. As rotary movement of the spindle 4 is positively prevented and as the tube cap is clamped by the pincher mechanism formed by the button 5 and the hooks 15 with a sufficient yielding pressure, the tube A cannot turn about its axis when being moved by the elevator mechanism. This may be particularly important where the angular position of the tube relative to the conveyor has been previously defined with respect to a print, label or the like on the tube.

When the spindle 4 has been moved downwardly so that the holder 14 again rests on the guide 19 the holder 14 will yield and the pincher mechanism will assume the position shown in Fig. 1, 20 whereafter the conveyor 2 moves the holder 1 together with the filled tube in a sidewise direction out of the elevator mechanism. The operation is then repeated in the next tube to be filled.

I claim:—

25 1. In an apparatus for elevating capped tubes or similar containers, a longitudinally movable spindle, a supporting member on an end of said spindle, a ring on said spindle, a yielding means enclosing said spindle between said supporting member and said ring to urge said ring away from said supporting member, and hooks secured to said ring and projecting inwardly beyond said supporting member.

2. In an apparatus for elevating capped tubes or similar containers, a longitudinally movable spindle, a supporting member on an end of said spindle, a ring on said spindle, a contractile spring on said spindle interposed between said supporting member and said ring to urge said ring away from said supporting member, and hooks secured to said ring and projecting inwardly beyond said supporting member.

3. In an apparatus for elevating capped tubes or similar containers, a stationary guide, a spindle axially movable in said guide, a supporting member on said spindle, a ring axially movable between said guide and said supporting member, a yielding means enclosing said spindle between said supporting member and said ring to urge said ring against said guide, and hooks secured to said ring and projecting inwardly beyond said supporting member.

4. In an apparatus for elevating capped tubes or similar containers, a stationary guide, a supporting spindle axially movable in said guide, a ring axially movable on said spindle, and hooks secured to said ring and projecting inwardly beyond the end of said spindle.

5. In an apparatus for elevating capped tubes or similar containers, a longitudinally movable supporting spindle, a member axially movable on said spindle, and hooks on said member, said hooks projecting inwardly beyond an end of said spindle.

25 BROR EMIL JOHNSON.
